UNITED STATES PATENT OFFICE.

BENJAMIN J. GUNDERSON, OF SPRING GROVE, MINNESOTA.

MEASURING CANISTER.

Application filed May 3, 1924. Serial No. 710,818.

The present invention has for its object to provide a canister or other container adapted to receive tea, coffee, baking powder, salt and the like with a measure, whereby a pre-determined amount may be delivered while at the same time protecting the contents of the canister from the atmosphere which may have a deteriorating effect thereon.

Other objects and advantages will be apparent and suggest themselves as the nature of the invention is understood.

While the drawings illustrate an embodiment of the invention it is to be understood that in adapting the same to meet different conditions and requirements, various changes in the form, proportion and minor details of construction may be resorted to without departing from the spirit of the invention.

Referring to the accompanying drawings forming a part of the application:

Figure 1 is a plan view of a canister provided with a measure embodying the invention.

Figure 2 is a side elevation.

Figure 3 is a longitudinal sectional view, on the line 3—3 of Figure 1.

Figure 4 is a longitudinal sectional view showing the device in inverted position with the drum turned to filling position.

Corresponding and like parts are referred to in the following description and designated in the several views of the drawings by like reference characters.

The numeral 1 designates the body of a canister, box or other container adapted to receive tea, coffee, baking powder or other article which it is desirable to deliver in measured quantity and at the same time prevent exposure to the atmosphere. The top or cover 2 is provided with the measuring device and has a rectangular opening 3 formed therein. Disks 4 are located at opposite ends of the opening 3 and are disposed in parallel relation and project above and below the top or cover. Circular plates 5 are arranged at opposite sides of the opening 3 and attached at their ends to the edges of the disks 4, and these plates are equally spaced to provide a top opening 6 and a

bottom opening 7, and these openings are of like size. A circular drum 8 is arranged in the opening 3 and obtains a snug fit between the disks 4 and plates 5. An opening 9 is formed in a side of the drum 8 and corresponds in size with the openings 6 and 7 and is adapted to register therewith. A shaft 10 is mounted in the disk 4 and is located exterior to the top or cover 2 and is provided at one end with a stop 11 and at the opposite end with a knob 12 which provides convenient means for rotating the shaft and the drum 8 mounted thereon and made fast thereto. The shaft 10 and drum 8 have a partial rotary movement which is limited in each direction by the stop 11 engaging the top or cover 2. In one position of the drum, its opening 9 registers with the bottom opening 7, thereby admitting of the drum receiving a portion of the contents of the canister or analogous container. In the other extreme position of the drum, its opening 9 registers with the opening 6, thereby admitting of the drum discharging its contents. The drum 8 constitutes the measuring vessel and may be of any required capacity.

What is claimed is:

A container provided with a rectangular opening through a wall thereof, disks disposed at opposite ends of the opening, arcuate plates arranged at opposite sides of said opening, said disks and plates being disposed partly interiorly and partly exteriorly of the container and coacting to provide discharge ways one interiorly of the container and the other exteriorly thereof, a rotary measuring vessel snugly fitting between the said disks and plates and having an opening therein, said vessel having a shaft journaled in said disks, said shaft being exteriorly of the wall of the container, and a substantially rectangular stop element on one end of the shaft engageable at opposite sides with said wall to limit its rotation in each direction to thereby insure registration of the opening of the measuring vessel with said ways.

In testimony whereof I affix my signature.

BENJAMIN J. GUNDERSON.
